UNITED STATES PATENT OFFICE

110,806

DESIGN FOR A BACON GRILL

Robert G. Fishel, Evanston, Ill.

Application February 21, 1938, Serial No. 75,306

Term of patent 14 years

To all whom it may concern:

Be it known that I, Robert G. Fishel, a citizen of the United States, residing at 942 Michigan Avenue, Evanston, county of Cook and State of Illinois, have invented a new, original, and ornamental Design for a Bacon Grill, of which the following is a specification, reference being had to the accompanying drawing, forming part thereof.

Fig. 1 is a perspective view of a bacon grill showing my new design; and Fig. 2 is a sectional view taken along the line 2—2 of Fig. 1.

I claim:

The ornamental design for a bacon grill, as shown.

ROBERT G. FISHEL.
